UNITED STATES PATENT OFFICE.

CHARLES ZIEGLER, OF LIMOGES, FRANCE, ASSIGNOR TO THE J. POUYAT COMPANY, OF NEW YORK, N. Y.

DESIGN FOR A VASE OR SIMILAR ARTICLE.

41,362.

Specification for Design.

Patented May 9, 1911.

Application filed March 7, 1910. Serial No. 547,943. Term of patent 7 years.

To all whom it may concern:

Be it known that I, CHARLES ZIEGLER, a citizen of France, residing in Limoges, France, have invented a new, original, and ornamental Design for a Vase or Similar Article, of which the following is a specification, reference being had to the accompanying drawings, forming a part thereof.

Figure 1 is a front view of a vase or similar article showing my design; Fig. 2 is a side view of the same; and Fig. 3 is a side view of the same.

I claim:

The ornamental design for a vase or similar article as shown.

CHARLES ZIEGLER.

Witnesses:

PAUL PERNAUD,
CHARLES R. NASMITH.
